CHARLES O. BULOCK AND BERTRAM C. DONNELLY, OF MILWAUKEE,
WISCONSIN.

TELESCOPIC LIFT.

SPECIFICATION forming part of Letters Patent No. 660,091, dated October 23, 1900.

Application filed February 5, 1900. Serial No. 3,931. (No model.)

To all whom it may concern:

Be it known that we, CHARLES O. BULOCK and BERTRAM C. DONNELLY, of Milwaukee, in the county of Milwaukee and State of Wisconsin, have invented a new and useful Improvement in Telescopic Lifts, of which the following is a description, reference being had to the accompanying drawings, which are a part of this specification.

10 Our invention has relation to improvements in telescopic lifts.

The object of the invention is to provide a construction of such character that the lifting mechanism under normal conditions will 15 take up but a small amount of vertical space, and yet at the same time will provide for a considerable travel of the load.

With the above primary object in view the invention consists of the devices and parts 20 or their equivalents, as hereinafter more fully set forth.

In the accompanying drawings, Figure 1 is a vertical sectional view of the invention. Fig. 2 is an outer end view of the valve mechanism. Fig. 3 is a plan view of Fig. 2, partly in horizontal section. Fig. 4 is an outer face view of the valve-seat. Fig. 5 is a section of the valve and of the valve-seat with the inlet ports and passages in register. Fig. 6 is 30 a detail view looking on the inner face of the valve. Fig. 7 is a view of the inner end of the valve-stem, and Fig. 8 is a view of the outer face of the valve.

Referring to the drawings, the numeral 9 35 indicates an outer cylinder, provided at its top with a crown-plate 10, which plate is preferably provided with a depending flange, which surrounds and has, preferably, a threaded connection with the upper end of the cylinder.

40 To the crown-plate is connected a hook 11, adapted to suspend the lift from any desirable point of suspension. The crown-plate is also provided with a vent-opening 12. At the lower end of the outer cylinder is a lower head 45 13, preferably having a threaded connection with the cylinder. The horizontal or bottom portion of this head is provided with a large opening 14.

The numeral 15 indicates an inner cylinder, the circumference of which is sufficiently 50 less than the circumference of the outer cyl-

inder, so as to form a chamber or space 16 between the two cylinders when said cylinders are telescoped, as shown in Fig. 1. At the upper end of the inner cylinder is a follower-plate 17. The circumferential edge of this follower-plate fits against the inner side of the outer cylinder. This plate is also provided with a vent-opening 18. Surrounding the inner cylinder a slight distance below the follower-plate 17 is an inverted-L-shaped 55 flange 19, which forms a piston-head. Between the horizontal portion of this flange and the under side of the portion of the follower-plate which projects beyond the inner cylinder is a packing 20, of leather or other desirable material. The outer edge of this packing is advisably turned downwardly into the space between the inner side of the outer cylinder and the edge of the horizontal portion of the flange. A pressure upward against the flange therefore will serve to press this turned-down edge of the packing tightly 60 against the wall of the outer cylinder, and hence provide effectually against the escape 65 of the actuating medium. The packing 20 is held in place by means of bolts or equivalents 21, 22, and the packing is thus made to form a tight joint between the two cylinders.

The numeral 22 indicates the lower head of 70 the inner cylinder. Beneath the horizontal portion of the lower head 13 of the outer cylinder is a packing 23, of leather or other desirable material, and beneath this packing is arranged an annular plate 24, the packing 75 being clamped between said plate and the head 13 by means of bolts or equivalents 25, whereby a tight joint is provided. The bordering edge of the circular opening of the packing 23 is turned upwardly, as clearly 80 shown, and this upwardly-turned edge is disposed between the inner edge of the horizontal portion of the lower head 13 and the lower end of the inner cylinder. By this provision whenever the actuating medium is admitted 85 into the chamber 16 it presses against the upturned edge of the packing, and thereby causes the same to bear tightly against the inner cylinder and effect a tight joint. Fitted to the central opening of the lower head 90 22 of the inner cylinder is a stuffing-box 26. Within the inner cylinder is adapted to work 95 100

a piston-head 27, and from this piston-head depends a piston-rod 28, said rod extending freely through the stuffing-box 26 and carrying at its lower end a swivel attachment 29, 5 said swivel attachment carrying a hook 30, which is adapted to engage the load to be elevated. A channel 31 extends through the lower head and stuffing-box 13 and communicates at its inner end with the chamber or 10 space 16.

Any desired form of valve mechanism for admitting the actuating agent into and exhausting the same from the space 16 may be provided; but we prefer to employ the construction now about to be described.

Fitted to the lower head 13 of the outer cylinder is a valve-seat 32. A separate valve-seat, however, is not absolutely necessary, as said seat could be formed on the head 13. 20 Fitted to the valve-seat is a valve-casing 33. The casing and seat are held together and to the head 13, preferably, by means of bolts 34. Within the valve-chamber 35 of the casing is arranged a rotatable valve 36. The valve-seat is provided with two inlet-ports 37 37', the former being somewhat larger in circumference than the latter and the two connected by means of a connecting-channel 38, and leading from this connecting-channel outwardly through the peripheral edge of the seat is a short channel 39, which communicates with the valve-chamber 35. The inner face of the valve is provided with an inwardly-extending journal 40, which fits in a 25 central opening in the valve-seat, said opening thereby forming a bearing for the journal. This journal is provided with a channel 41. The outer end of the channel 41 has a channel 42 extending therefrom at an angle 30 through the valve, said channel 42 being shown in the drawings as also in communication with the ports 37 37'. The inner end of the channel 41 communicates with a port 43 in the valve-seat, and this port 43 in turn 35 communicates with the channel 31.

The numeral 44 indicates an inlet pipe or conduit for the actuating medium, and this pipe communicates at its lower end with a channel 45 in the head 13. The valve-casing is also provided with two other ports 46 46', the former being somewhat larger in circumference than the latter, and these ports are in communication with each other by means of a connecting-channel 47. The two 50 ports 46 46' are also in communication with a final exhaust-channel 48, which extends outwardly through the edge of the valve-seat.

While the journal 40, projecting from the inner face of the valve, is advisably provided, 55 yet it is not absolutely necessary. If omitted, the channel 42 would then communicate directly with the channel 43.

The valve-stem is indicated by the numeral 49 and extends outwardly through the outer 60 end of the casing. The inner end of the stem is formed or provided with a flange 50, which fits against the outer wall of the valve-

chamber and prevents withdrawal of the valve-stem. The outer face of the valve is formed with two lugs 51 51, which form therebetween a recess to receive a key 52 on the inner face of the flange 50. By this arrangement the rotation of the valve-stem will impart rotation to the valve. The valve-stem is tubular for a desired distance from its inner end outwardly, and fitted in this tubular portion is a spring 53. The inner end of this spring bears against the outer face of the valve, and thereby assists in holding the valve close to its seat. The outer end of the 70 valve-stem is provided with two arms 54 54', extending therefrom in such manner as to form practically a bell-crank lever. From the arm 54 is a pendent chain 55 and from the arm 54' is a pendent chain 55'. The valve-casing is also formed or provided with a quadrant 56. The curved edge of this quadrant is formed with intermediate shoulders 57 57' and with end shoulders 58 58'. The inner side of the arm 54 carries a spring-actuated dog 59, which is adapted to work over the curved edge of the quadrant. A spring is wound about a pin 60, and the ends of this spring are extended to form the spring-arms 61 61'. The ends of these arms normally 90 bear against a stud 62, projecting from the quadrant. The arm 54 has extending inwardly therefrom a finger 63, which is adapted to engage either the spring-arm 61 or 61', in accordance with whether the chain 55 or 100 55' is operated.

The operation of our invention will now be described. It will be supposed that a pull has been exerted on the chain 55 and this has caused a down movement of the arm 54, 105 and consequently a turning of the valve to the left. The turning to the left is first impeded by contact of the dog 59 with the intermediate shoulder 57. The moment this contact occurs the channel 42 of the valve will 110 be brought into register with the port 37' of the valve-seat, and hence the inlet air or other actuating medium is free to flow through the pipe 44, passage 45, port 37', thence by way of channels 42 41, port 43, and channel 31 115 into the chamber or space 16. The flow of the actuating medium through the contracted channel 37' permits of a flow of the actuating agent sufficient for ordinary purposes. If, however, a greater flow of the actuating medium is required in order to obtain increased power a greater pull is exerted on the chain 55, and the dog 59 is thereby drawn from the shoulder 57 until said dog contacts with the shoulder 58, which shoulder 58 limits the extent of turning and brings the larger port 37 120 also into registration with the several passages or channels hereinbefore mentioned. In the position of the parts shown in the drawings this larger port 37 is in registration. It 125 will be supposed that when the valve was first adjusted in the manner just explained the piston-rod was already out to its full extent permitted by contact of the piston-head 27

with the lower head 22 of the inner cylinder, and the inner cylinder was also pulled out to the extent permitted by contact of the flange or piston-head 19 with the lower edge 13 of the outer cylinder. The actuating agent, therefore, which passes into the space 16 will first act on the piston-head 19 and cause a rising of the inner cylinder, the air above the follower-plate 17 escaping through the vent 12. When the inner cylinder is thus raised to its full extent, a port 64 at the lower end of the inner cylinder will be exposed to the chamber 16, and hence the actuating agent will be free to flow into said inner cylinder and act against the piston-head 27 and cause a rising of said piston-head and its piston-rod, the air above the said piston-head escaping through the vents 18 and 12. The telescoping portions at the completion of this operation are at the position shown in Fig. 1, and it is obvious that any load suspended from the hook 30 will be thereby elevated. Attention is also directed to the fact that when the inlet-ports and channels are in registration, as explained, the inlet actuating agent is also free to flow through the short channel 39 and enter the valve-chamber 35, so as to exert a pressure against the valve 36, and thereby counteract the pressure of the actuating agent against the inner face of the valve. The next step is for the operator to release the chain 55. The moment this release occurs the action of the spring-arm 61 against the finger 63 will cause a return of the two arms 54 and 54' to the normal position in which the two spring-arms 61 and 61' are in contact with the stud 62. At this normal position the ports of the valve are out of register both with the inlet and exhaust passages, and hence the telescoping parts are held up to the position to which they have been carried by the operation described. If now it is desired to exhaust the air or other actuating medium beneath the piston-head 27 and also beneath the piston-head 19, a pull is exerted on the chain 55'. This will cause a turning of the valve so as to bring the passage 42 thereof first into register with the small port 46', the intermediate shoulder 57' impeding the turning movement. The actuating agent is now free to exhaust from the interior cylinder through the port 64 into the chamber or space 16, thence through the passage 31, through the port 43, thence through the passage 41 of the trunnion of the valve, and thence by way of the passage 42 to the port 46', and finally from the port 46' through the exhaust passage or channel 48 to the external air. If a freer exhaust is required, a harder pull is exerted on the chain 55, so as to cause the dog 58 to ride past the shoulder 57' and contact with the shoulder 58'. This will also bring the larger port 46 into registration. It will be understood that with the turning of either the arm 54 or 54' the pin 63 thereof will contact with either the spring-arm 61 or 61' and carry the said spring-arm therewith, and that

when the chain is released the retractile power of the spring-arm will cause the valve to again assume a normal position. As the actuating agent is being exhausted in the manner just explained the hook 30 can be grasped and the piston-head 27 pulled outwardly or downwardly to its full extent or until it contacts with the lower head 22. A further pull on the hook 30 will then cause the inner cylinder 15 to descend, said cylinder being free to pass through the opening 14. With the continued pulling said cylinder is drawn out to its full extent or until the piston 19 contacts with the lower head 13 of the outer cylinder. The hook 30 can now engage the load to be elevated, and the parts are telescoped in order to elevate the load in the manner first explained. By allowing more area on the outer piston-head 19 than on the inner piston-head 27 the larger or outer piston-head 19 is caused to first lift and to travel the full length of the outer cylinder and remain in that position and that subsequently the inner piston-head is then caused to travel inwardly to its full extent.

We prefer to employ air as the actuating medium, but wish it understood that any other agent suitable for the purpose may be employed—such, for instance, as water, steam, gas, and the like.

While we have herein shown and described only one inner cylinder, yet we do not wish to be understood as limiting ourselves thereto, inasmuch as if it is desired that the lift in its normal telescoped condition shall consume the minimum vertical distance a plurality of the inner cylinders may be provided, connected one with the other through the medium of a port similar to 64 and the innermost of said cylinders having the piston 27, adapted to work therein. By employing a plurality of these inner cylinders the necessary extent of lift may be provided, while the device itself in its normal telescoped condition will require but the minimum of vertical height.

What we claim as our invention is—

1. In a telescopic lift, the combination of an outer casing provided with an opening through one of its end pieces, an inner casing movable through the open end of the outer casing, and of such less transverse area than the outer casing as to leave a space between the two casings, said inner casing provided at one end with a piston-head fitting against the wall of the outer casing, and the interior of the inner casing being normally in communication with the space between it and the outer casing, but out of communication therewith when said inner casing is pulled outwardly, a piston-head adapted to work in the inner casing and provided with a piston-rod extending through the end of the inner casing, and means for introducing an actuating agent into the interior of the outer casing and for exhausting said actuating agent therefrom.

2. In a telescopic lift, the combination of

an outer casing provided with an opening through one of its ends, an inner casing movable through said opening, and of such less transverse area than the outer casing as to leave a space between the two casings, said inner casing provided at one end with a piston-head fitting against the wall of the outer casing, and the interior of the inner casing being normally in communication with the space between it and the outer casing, but out of communication with the space when said inner casing is pulled outwardly, a piston-head adapted to work in the inner casing and of less area than the area of the outer piston-head, said inner piston-head having a piston-rod extending therefrom and through the end piece of the inner casing, and means for introducing an actuating agent into the interior of the outer casing and for exhausting said actuating agent therefrom.

3. In a telescopic lift, the combination of an outer casing provided with an opening through one of its end pieces and having a hook connected to its opposite end piece, an inner casing movable through the opening in the end piece of the outer casing and of such less transverse area than the outer casing as to leave a space between the two casings, said inner casing provided at one end with a piston-head fitting against the wall of the outer casing, and the interior of the inner casing being normally in communication with the space between it and the outer casing, but out of communication with said space when the inner casing is pulled outwardly, a piston-head adapted to work in the inner casing, said inner piston-head having a piston-rod extending through the end piece of the inner casing, a hook connected to the outer end of the piston-rod, and means for introducing an actuating agent into the interior of the outer casing and for exhausting said actuating agent therefrom.

4. In a telescopic lift, the combination of an outer casing provided with an opening through one of its end pieces, an inner casing movable through the opening in the end piece and of such less transverse area than the outer casing as to leave a space between the two casings, said inner casing provided at one end with a piston-head fitting against the wall of the outer casing, and provided near its opposite end with a port in communication with the interior space of the outer casing when said inner casing is telescoped into the outer casing, a piston-head adapted to work in the inner casing, said piston-head having a piston-rod extending therefrom through the end piece of the inner casing, and means for introducing an actuating agent into the interior of the outer casing and for exhausting said actuating agent therefrom.

5. The combination of inner and outer parts, the outer part having its end piece provided with an opening into which the inner part extends, and said inner part being of such less transverse area than the outer

part as to leave a space between the two parts, a packing arranged beneath the end piece of the outer part, said packing provided with an opening surrounding the inner part, the bordering edge of said packing being upturned, and said upturned edge being arranged between the inner part and the bordering edge of the opening of the end piece, and a plate bearing against the packing and clamping the same to the end piece.

6. In a telescopic lift, the combination of an outer casing provided with an opening through one of its ends, an inner casing movable through said opening, and of such less transverse area than the outer casing as to leave a space between the two casings, said inner casing provided at one end with a piston-head fitting against the wall of the outer casing, and the interior of the inner casing being normally in communication with the space between it and the outer casing, but out of communication with said space when the inner casing is pulled outwardly, a piston-head adapted to work in the interior casing, said piston-head having a piston-rod extending therefrom and through the end piece of the inner casing, a valve-casing having an inlet-channel for the actuating medium leading thereto, a valve-seat provided with an inlet-channel leading to the interior space of the outer casing and with an exhaust-channel leading to the external atmosphere, a valve fitting in the valve-chamber of the valve-casing, and provided with a channel which is normally out of register with both the inlet and exhaust channels, and means for turning the valve, whereby when turned in one direction the channel thereof connects the inlet-channel with the channel leading to the interior space of the outer casing, and when turned in the opposite direction the channel thereof connects the channel leading to the interior space of the outer casing with the exhaust-channel.

7. In a telescopic lift, the combination of an outer casing provided with an opening through one of its ends, an inner casing movable through said opening, and of such less transverse area than the outer casing as to leave a space between the two casings, said inner casing provided at one end with a piston-head fitting against the wall of the outer casing and the interior of the inner casing being normally in communication with the space between it and the outer casing, but out of communication with said space when the inner casing is pulled outwardly, a piston-head adapted to work in the inner casing, said piston-head having a piston-rod extending through the end piece of the inner casing, a valve-casing having an inlet-channel for the actuating medium leading thereto, a valve-seat provided with two leads, one larger than the other and communicating with the inlet-channel leading to the interior space of the outer casing, and said valve-seat also provided with an exhaust-channel leading to the

external atmosphere, a valve fitting in the valve-chamber of the valve-casing, and provided with a channel which is normally out of register with both the inlet and exhaust channels, and means for turning the valve, whereby when turned in one direction the channel thereof connects the inlet-channel with the channel leading to the interior space of the outer casing, and when turned in the opposite direction the channel thereof connects the channel leading to the interior space of the outer casing with the exhaust-channel.

8. In a telescopic lift, the combination, of an outer casing provided with an opening through one of its ends, an inner casing movable through said opening and of such less transverse area than the outer casing as to leave a space between the two casings, said inner casing provided at one end with a piston-head fitting against the wall of the outer casing, and the interior of the inner casing being normally in communication with the space between it and the outer casing, but out of communication with said space when the inner casing is pulled outwardly, a piston-head adapted to work in the inner casing, said piston-head having a piston-rod extending through the end piece of the inner casing, a valve-casing having an inlet-channel for the actuating medium leading thereto, a valve-seat provided with an inlet-channel leading to the interior space of the outer casing, and also provided with an exhaust-channel leading to the external atmosphere, said exhaust channel having two leads leading thereto, one being larger than the other, a valve fitting in the valve-chamber of the valve-casing and provided with a channel which is normally out of register with both the inlet and exhaust channels, and means for turning the valve, whereby when turned in one direction the channel thereof connects the inlet-channel with the channel leading to the interior space of the outer casing, and when turned in the opposite direction the channel thereof connects the channel leading to the interior space of the outer casing with the exhaust-channel.

9. In a telescopic lift, the combination, of an outer casing provided with an opening through one of its ends, an inner casing movable through said opening and of such less transverse area than the outer casing as to leave a space between the two casings, said inner casing provided at one end with a piston-head fitting against the wall of the outer casing, and the interior of the inner casing being normally in communication with the space between it and the outer casing, but out of communication with said space when the inner casing is pulled outwardly, a piston-head adapted to work in the inner casing, said piston-head having a piston-rod extending therefrom and through the end piece of the inner casing, a valve-casing having an inlet-channel for the actuating medium leading thereto, a valve-seat provided with an in-

let-channel leading to the interior space of the outer casing and with an exhaust-channel leading to the external atmosphere, a valve fitting in the valve-chamber of the valve-casing, a stem projecting from the valve through the outer end of the valve-casing, arms extending from the outer end of the valve-stem, one of said arms carrying a spring-actuated dog, a quadrant over which the dog is adapted to work, said quadrant provided with shoulders with which the dog is adapted to contact, the arms being normally in such position as to have the channel of the valve out of register with either the inlet or exhaust channels, but adapted when operated, and when the dog contacts with one of the shoulders, to bring the channel of the valve into register with the inlet-channels, or when operated in the opposite direction to bring the dog into contact with the other shoulder and thereby cause the channel of the valve to register with the exhaust-channels.

10. In a telescopic lift, the combination of an outer casing provided with an opening through one of its ends, an inner casing movable through said openings, and of such less transverse area than the outer casing as to leave a space between the two casings, said inner casing provided at one end with a piston-head fitting against the wall of the outer casing, and the interior of the inner casing being normally in communication with the space between it and the outer casing, but out of communication with said space when the inner casing is pulled outwardly, a piston-head adapted to work in the inner casing, said piston-head having a piston-rod extending through the end piece of the inner casing, a valve-casing having an inlet-channel for the actuating medium leading thereto, a valve-seat provided with two lead-ports one larger than the other, and both ports registering with the channel leading to the interior space of the outer casing, and said valve-seat also provided with two lead-ports one larger than the other registering with the exhaust-channel leading to the external atmosphere, a valve fitting in the valve-chamber, a stem projecting from the valve through the outer end of the valve-casing, arms extending from the outer end of the valve-stem, one of said arms carrying a spring-actuated dog, and a quadrant over which the dog is adapted to work, said quadrant provided with end shoulders and with intermediate shoulders, the arms being normally in such position as to have the channel of the valve out of register with either the inlet or exhaust channels, but adapted when operated, and when the dog contacts with one of the intermediate shoulders to bring its channel into register with the small inlet lead-port of the valve-seat, and when operated farther in the same direction to contact with the end shoulder and bring the valve-channel into register with the large inlet lead-port of the valve-seat, and when the arms are turned in the opposite direction the

contact of the dog with the other intermediate shoulder adapted to bring the channel of the valve into register with the small exhaust lead-port, and when turned farther until the 5 dog contacts with the other end shoulder to bring the channel of the valve into register with the large exhaust lead-port.

11. In a telescopic lift, the combination of an outer casing provided with an opening 10 through one of its ends, an inner casing movable through said opening and of such less transverse area than the outer casing as to leave a space between the two casings, said inner casing provided at one end with a piston-head fitting against the wall of the outer casing, and the interior of the inner casing being normally in communication with the space between it and the outer casing, but out of communication with said space when the 15 inner casing is pulled outwardly, a piston-head adapted to work in the inner casing, said piston-head having a piston-rod extending through the end piece of the inner casing, a valve-casing having an inlet-channel for the 20 actuating medium leading thereto, a valve-seat provided with an inlet-channel leading to the interior space of the outer casing, and also provided with an exhaust-channel leading to the external atmosphere, a valve fitting 25

in the valve-chamber of the valve-casing, a 30 stem projecting from the valve through the outer end of the valve-casing, arms extending from the outer end of the valve-stem, one of said arms carrying a spring-actuated dog, a quadrant over which the dog is adapted to 35 work, said quadrant provided with shoulders with which the dog is adapted to contact, the arm being normally in such position as to have the channel of the valve out of register with both the inlet and exhaust channels, but 40 adapted when operated, and when the dog contacts with one of the shoulders, to bring the channel of the valve into register with the inlet-channels, but when operated in the opposite direction to bring the dog into contact 45 with the other shoulder and thereby cause the channel of the valve to register with the exhaust-channels, and a spring adapted to act on the arms to return said arms, after being released, to normal position. 50

In testimony whereof we affix our signatures in presence of two witnesses.
